CLAIM

The ornamental design for a videophone base, as shown and described.

DESCRIPTION

FIG. 1 is a top, front and right side perspective view of a videophone base according to my design;
FIG. 2 is a left side elevational view thereof;
FIG. 3 is a rear elevational view thereof;
FIG. 4 is a right side elevational view thereof;
FIG. 5 is a bottom plan view thereof;
FIG. 6 is a right side elevational view, with the plinth in a reversed position to facilitate wall mounting; and,
FIG. 7 is a view similar to FIG. 1 with the display screen in a raised position.

Fig. 1.

*Fig. 2.**Fig. 3.**Fig. 4.*

*Fig. 5.**Fig. 6.**Fig. 7.*
